DESIGN FOR A SPOOL HOLDER

Clara W. Hogan, Fort Worth, Tex.

Application October 16, 1945, Serial No. 122,894

Term of patent 7 years

(Cl. D3—19)

To all whom it may concern:

Be it known that I, Clara W. Hogan, citizen of the United States of America, residing at Fort Worth, in the county of Tarrant and State of Texas, have invented a new, original, and ornamental Design for a Spool Holder, of which the following is a specification, reference being had to the accompanying drawing, forming part thereof.

I claim:

The ornamental design for a spool holder, as shown.

CLARA W. HOGAN.
